US0D1030425S

(12) **United States Design Patent** (10) **Patent No.:** **US D1,030,425 S**
(45) **Date of Patent:** **** Jun. 11, 2024**

(54) **VEGETATION HANGER**

(71) Applicant: **DriFlower, LLC**, Ashland, OR (US)

(72) Inventor: **Todd Chandler Larkins**, Ashland, OR (US)

(73) Assignee: **DRIFLOWER, LLC**, Ashland, OR (US)

(**) Term: **15 Years**

(21) Appl. No.: **29/824,054**

(22) Filed: **Jan. 21, 2022**

Related U.S. Application Data

(63) Continuation of application No. 17/066,633, filed on Oct. 9, 2020.

(51) **LOC (14) Cl.** **08-11**

(52) **U.S. Cl.**

USPC **D8/373; D8/1; D8/371**

(58) **Field of Classification Search**

USPC D8/373, 371, 1; D6/327

CPC A01G 17/06; A01G 17/08; A01G 17/14;

A01G 2017/065
